(57) **CLAIM**

The ornamental design for a lid, as shown and described.

DESCRIPTION

FIG. 1 is a top front perspective view of a lid showing our new design;

FIG. 2 is a front view thereof and the rear view being a mirror image;

FIG. 3 is a left side view thereof and the right side view being a mirror image;

FIG. 4 is a top view thereof;

FIG. 5 is a bottom view thereof;

FIG. 6 is an enlarged cross-sectional view thereof, taken along line 6-6 in FIG. 4; and,

FIG. 7 is a bottom front perspective view thereof.

The relatively thin shade lines show contour and not surface ornamentation.

1 Claim, 6 Drawing Sheets
